UNITED STATES PATENT OFFICE.

SHINTARO YOKOZUKA, OF NEW YORK, N. Y., ASSIGNOR TO E. T. MASON & CO., OF SAME PLACE.

DESIGN FOR FABRIC.

SPECIFICATION forming part of Design No. 26,085, dated September 22, 1896.

Application filed August 15, 1896. Serial No. 602,911. Term of patent 3½ years.

To all whom it may concern:

Be it known that I, SHINTARO YOKOZUKA, a subject of the Emperor of Japan, residing in the city, county, and State of New York, have invented and produced a new and original Design for Fabrics, of which the following is a specification, reference being had to the accompanying drawing, forming a part thereof, which represents a face view of a piece of fabric in which the new design is embodied.

The design consists in a surface decoration simulating lacework, having as characteristic features web and scarf patterns.

I claim—

The design for a fabric herein shown and described.

SHINTARO YOKOZUKA.
